Filed Sept. 13, 1974, Ser. No. 505,665

Term of patent 14 years

Int. Cl. D6—06

U.S. Cl. D6—191

FIG. 1 is a perspective view of a lounge chair frame showing my design;

FIG. 2 is a top view illustrating the diametrical difference between the upper circular frame and the lower circular base;

FIG. 3 is a left side view with the right side view being a mirror image thereof and illustrating the angled relationship between the upper circular frame and the circular base frame; and

FIG. 4 is a view in front elevation thereof.

I claim:

The ornamental design for a lounge chair frame, as shown and described.
